WINDMILL AND PUMP REMOTELY
OPERATED THEREBY

Renwick J. Sharp, Guatemala, Guatemala

Application November 18, 1943, Serial No. 510,821

16 Claims. (Cl. 170—75)

This invention relates to a pump remotely operated by a windmill.

In many localities where the terrain is broken and abrupt, especially along streams or where seepages occur at the foot of hills or adjacent to elevated plots of ground, many systems, some of them windmill operated, have been devised for lifting the water out of the low places and storing it at higher levels. These systems in many instances have proved to be of an impractical, unsatisfactory character. This has been due to a number of different causes, among them being the necessity for drilling very deep wells where it was deemed necessary to locate a windmill upon a hilltop and also to position the well directly thereunder: also wells so drilled often fail to afford access to the abundant supply of water desired which supply would have been readily available had connection been made with the streams, pools, or seepage often encountered adjacent to the foot of the hill upon which it was desired to locate the windmill, but horizontally remote from a line perpendicular to the desired windmill site.

Another defect of pumping systems for localities like those above mentioned has been due to the provision of windmills located in low wind-sheltered positions, so as to be nearer to the water to be pumped, but necessarily provided with large, expensive windwheels to offset the lack of wind available in such situations.

It is among the more important objects of the invention to overcome the aforementioned disadvantages and others by providing means for elevating water from a lowland to a highland by placing the operating unit at a remotely situated higher level as well as at a considerable horizontal distance from the pumping unit, thereby minimizing the size of the operating unit, the depth of well drilling and the size and weight of pumping units required.

Among other important objects are: To provide as a connecting medium between the operating and pumping units an improved power transmitting connection; to improve upon the guide, supporting and operating means utilized in conjunction with said power transmitting connection; to gain additional wind power through selective sites of elevated terrain, and to lessen and make easier the task of making repairs and replacements and reducing the cost of such installations which for the reasons advocated have heretofore made such water pumping and raising prohibitive.

Another and more specific object is to provide

an improved means to reinforce or stabilize a power transmitting rod which is vertically positioned within a windmill tower and serves to transmit power from the windwheel to an oscillatory power transmitting wheel located therebelow.

The invention includes a power transmission means utilizable in other situations than the one illustrated in the drawing.

10 Other objects, advantages and features of invention will hereinafter appear.

Referring to the accompanying drawing, which illustrates what is at present deemed to be a preferred embodiment of the invention,

15 Fig. 1 is a perspective view of the complete apparatus.

Fig. 2 is a vertical section of the power transmission wheel, the plane of section being indicated by angular line 2—2 on Fig. 3, the cable-attaching device being shown in a spaced relation to the part of the wheel to which it is attachable.

Fig. 3 is a side elevation of the structure shown in Fig. 2.

20 Fig. 4 is a perspective view of the means for stabilizing against buckling the power transmission rod of the windmill.

Referring in detail to the drawing, upon the upper part of the tower 5 is turnably mounted a gear casing 6 one end of which carries a conventional wind wheel 7 fixed to the shaft 8, the opposite end of said casing carrying the conventional tail 9 whereby the wind wheel is directed toward the wind.

25 The reduction gearing within the casing 6 is operatively connected with the upper end of a vertical power transmission rod 11, the lower end of said rod being eccentrically pivoted to a large power transmission wheel 12 having a spindle or shaft portion 13 whereby it is turnably supported upon the lower part of the tower 5 to be oscillated in a vertical plane by said rod 11.

30 A pump 14 is shown remotely positioned in relation to the tower 5 both as to downward and as to horizontal distance, said pump being operatively connected with the aforesaid power transmission wheel 12 by means of an inclined cable 15, the upper end portion of said cable being attached to an upper side portion of said wheel 12 and the opposite end portion being led over the pump pulley 16 and farther on having a vertical run 17 secured to the pump rod 19 which is arranged for vertical reciprocation.

35 The pump structure includes a cement base 20 from which upstands a frame 21 upon the upper parts of which is mounted the aforesaid pulley

16 to turn in a vertical plane. The connection between the pump or piston rod 19 and the vertical run 17 of the cable includes a weight 22 which aids in keeping taut the cable 15 and also insures a positive downward movement of the vertically reciprocating piston rod 19 of the pump. Said weight is shown carrying a horizontal guide pin 23 with which cooperates a vertical slot 24 formed in a vertical guide plate 25 carried by the pump frame 21. The upper part of the cable 15 is shown having a downwardly directed terminal run 26 to which is secured a weight 27 which counterbalances the weight of the cable 15 and the weight 22.

The pump 14 may either be located above a well or adjacent to a pool of water, such well or pool being at the foot of the hill 29 upon which the tower 5 is built. A tank 30 is shown stationed on the top of this hill adjacent to said tower. From the pump 14 up the side of said hill to said tank leads a conduit 31 whereby said tank is supplied from said well or pool.

Referring to various mechanical details, the cable 15, if properly supported will operate efficiently even if several hundred feet in length, hence is shown passing between and supported by a plurality of pairs of antifriction guide pulleys 32 carried by posts 33.

Also, the power transmission rod 11 of the windmill is shown stabilized by being linked to a rockable rod 35 which is carried by the tower members 5a. Said rod carries a laterally extending staple-like link 36 which interlinks with a shorter U-shaped link 37 carried by the rod 11. This arrangement protects the long rod 11 against buckling and yet allows it to shift laterally to some extent, as it must in imparting oscillatory movement to the wheel 12 with which it is eccentrically connected. Said rod 11 is preferably made tubular in order to obtain maximum strength with minimum weight.

A cable clamping means is illustrated in the upper portions of Figs. 2 and 3, which includes a horizontal clamping bar 40 having a down-bent central portion 41, said bar having apertured end portions through which pass clamp screws 42 of the cap screw type which screw into threaded sockets 43 provided for them in the side portions of the power transmission wheel 12. Said wheel is preferably of the light hollow type as best shown in Fig. 2, where it is seen to have a plate like side portion cast integral with its spindle 18 and to have a thick, substantial rim portion 44 along the midwidth of which extends the cable-receiving groove 45. The cable 15 occupies the inner portion of this groove and the down-bent part 41 of the clamping bar 40 occupies the outer part of said groove and is clamped down against the cable under a sufficient pressure to insure that the latter will not slip during the operation of the pump. The power transmission wheel affords an efficient means for operatively connecting the lower end portion of the rod 11 with the upper end portion of the cable 15 so as intermittently to impart upward tractive movement to the latter in opposition to the weighted piston rod 18 to which the lower end portion of said cable is connected.

It is desirable to provide for operatively connecting the lower end of the power transmission rod 11 with the power transmission wheel at different distances from its center, the connection being made more eccentric for light winds and closer to the center when the windmill is being operated by a strong wind. With this end in

view the wheel 12 is provided with a series of seats formed by pivot holes 47 (three in the present embodiment) which are differently spaced from the center of said wheel, and in Figs. 2 and 3 the connection between the rod 11 and wheel 12 includes a pivot stud 48 extending through the outermost of the three holes shown, onto which screws a securing nut 49.

The operation of the apparatus will be readily understood from the foregoing description. However, an appreciation of the merits of the invention requires that it be observed that the windmill can be stationed upon a hill of considerable height, where the wind is much stronger and more constant than at lower levels, and yet the cable 15 can be extended over sloping terrain several hundred feet in length down to a pump stationed by a pool of water, or by a well much less in depth than would be required if the well were drilled at the elevated point where the windmill is stationed.

The apparatus is of a simple, sturdy, durable character, and is particularly serviceable in tropical and semi-arid countries, and in hilly regions. By providing the pump with a long piston cylinder lineal expansion and contraction of the cable due to changes in temperature can be taken care of.

When this apparatus is equipped with a wind-wheel eight feet in diameter, if driven by a good breeze, it is capable of lifting daily over five hundred gallons of water a vertical distance of 340 feet through a 1 1/4 inch pipe.

It should be understood that the present disclosure is for the purpose of illustration only and that this invention includes all modifications and equivalents which fall within the scope of the subject matter claimed.

What is claimed is:

1. In a windmill and device remotely operated thereby, a tower, a wind wheel carried by the upper part of said tower, a power transmission wheel mounted in the lower part of said tower to turn in a vertical plane, means operatively connecting said wind wheel with said power transmission wheel at differently adjustable distances from its axis of rotation to compensate for varying wind velocities, to oscillate the latter, a device remotely positioned in relation to said tower both as to downward and horizontal distance, and a cable one end of which is operatively connected with said power transmission wheel and the opposite end of which is operatively connected with said device, said cable being weighted to maintain it taut during the operation of said device.
2. In a windmill and device remotely operated thereby, a tower, a wind wheel carried by the upper part of said tower, a power transmission wheel mounted in the lower part of said tower to turn in a vertical plane, means operatively connecting said wind wheel with said power transmission wheel at differently adjustable distances from its axis of rotation to compensate for varying wind velocities, to oscillate the latter, a device remotely positioned in relation to said tower both as to downward and horizontal distance, and a cable one end portion of which is operatively connected with said device, its opposite end portion extending over and partly around said power transmission wheel, and a clamp carried by the latter wheel to secure the last recited end portion of said cable thereto.
3. In a windmill and device remotely operated thereby, a tower, a wind wheel mounted upon

said tower, a power transmission rod extending downwardly from said wind wheel and having its upper end operatively connected therewith, a cable extending from said tower to a point horizontally and downwardly remote from said tower, means operatively connecting said power transmission rod and cable intermittently to impart upward tractive movement to the latter, a device having a weighted piston rod connected with the lower end portion of said cable, and a counterweight connected to the upper portion of said cable and tending to draw it upwardly in opposition to the weight of said piston.

4. In a windmill and device remotely operated thereby, a tower, a wind wheel mounted upon said tower, a power transmission rod extending downwardly from said wind wheel and having its upper end operatively connected therewith, a cable extending from said tower to a point horizontally and downwardly remote from said tower, means operatively connecting said power transmission rod and cable intermittently to impart upward tractive movement to the latter, a device to be operated comprising a frame and a vertically reciprocating rod, a pulley carried by said frame over which the lower end portion of said cable extends and from which it is continued downwardly as a vertical run which is connected at its lower end to said reciprocating rod, a weight carried by the upper part of said reciprocating rod, and a weight attached to said cable in a position to accelerate said upward movement of said cable.

5. The subject matter of claim 4, and said frame having a guide member provided with a vertical slot, and a guide pin carried by said weight and projecting through said slot.

6. In a windmill and device remotely operated thereby, a tower, a wind wheel mounted upon said tower, a power transmission wheel mounted upon said tower below said wind wheel to turn in a vertical plane, a vertically extending rod having its lower end pivotally and eccentrically connected adjustably with said power transmission wheel to oscillate the latter in accordance with different wind velocities, a reduction gearing whereby the upper ends of said rod is operatively connected with said wind wheel, a device to be operated remotely stationed in relation to said tower both as to downward and horizontal distance, said device having a vertically reciprocating rod, a pulley mounted on said device above said piston rod, and a cable passing over said pulley, one end of said cable being connected to said reciprocating rod and its opposite end being operatively connected to said power transmission wheel.

7. In a wind-operable device for mechanically transmitting power, a tower, a wind wheel mounted upon said tower, a power transmission wheel mounted upon said tower below said wind wheel to turn in a vertical plane, a vertically extending rod having its lower end pivotally and eccentrically connected with said power transmission wheel to oscillate the latter, and a pair of loosely interlocked links to safeguard said rod against buckling, one of said links being swingably carried by the mid-length portion of said rod and the other of said links being swingably mounted upon said tower, said links swinging in a vertical plane and being positioned to accommodate themselves to the lateral movement of said rod due to its eccentric connection with said power transmission wheel.

8. The subject matter of claim 7, and said ver-

tical plane in which said links swing being substantially the same as the plane in which said power transmitting wheel oscillates.

9. Flexible transmission for delivering power from a windmill to a device to be operated comprising, a power transmission wheel mountable in the lower part of a windmill tower to turn in a vertical plane, said wheel having seats formed in it at different distances from its center, a cable one end portion of which is operatively connected with said wheel, and a device to be intermittently raised against the opposition of gravity stationed remotely from said wheel both downwardly and horizontally with which the opposite end of said cable is operatively connected, said cable being weighted to maintain it taut during the operation of said device.

10. Flexible transmission for delivering power from a windmill to a device to be operated comprising, a power transmission wheel mountable in the lower part of a windmill tower to turn in a vertical plane, said wheel having seats formed in it at different distances from its center, a cable one end portion of which is operatively connected with said wheel, said end portion of said cable extending over and partly around said wheel and being weighted to maintain it taut during the intermittent raising against the opposition of gravity of a device to be operated, a clamp carried by said wheel to secure the last recited end portion of said cable thereto, and a pulley located below the level of said wheel and horizontally remote therefrom, said cable having an end portion passing over said pulley and thence downward for connection to said device.

11. In a power transmission mechanism, a cable extending from an elevated point to a point horizontally and downwardly remote therefrom, counterweighted wind-mill operable means located at said elevated point and operatively connected with said cable intermittently to impart to it an upward tractive movement, a frame located at said downwardly remote point, a pulley supported by said frame in a vertical frame, said cable being continued downwardly over and from said pulley as a vertical run, and a weight connected to the lower end of said cable.

12. The subject matter of claim 11, and said frame having a guide member provided with a vertical slot, and a guide pin carried by said weight and projecting through said slot.

13. In a windmill operable mechanism, a power transmission wheel mountable in a windmill tower to turn in a vertical plane, a power transmission rod having one end portion operatively connectable with a windwheel to impart reciprocating movement to said rod, means carried by said power transmission wheel to connect pivotally thereto the opposite end portion of said rod at different adjustable distances from the axis about which said power transmission wheel turns, thereby to compensate for different velocities of wind to which the windwheel is exposed, a device to be operated, and flexible means operatively connecting said power transmitting wheel to said device to be operated in such a manner that the latter is raised and lowered in synchronism with the reciprocating of said power transmitting rod.

14. The subject matter of claim 13, and said means for connecting said power transmission wheel with said device to be operated comprising a cable one end portion of which is connected to said device to be operated and the opposite

end portion of which is alternately windable upon and unwindable from said power transmission wheel.

15. In a windmill operable pumping mechanism, a power transmission wheel mountable in a windmill tower to turn in a vertical plane, a power transmission rod having one end portion operatively connectable with a windwheel to impart reciprocatory movement to said rod, an operative connection to connect the opposite end portion of said rod to said power transmission wheel, said connection comprising holes in said power transmission wheel at different distances from its center and a pivot stud adjustable to different said holes, thereby to connect adjustably said rod and power transmission wheel to compensate for different velocities of wind to which the windwheel is exposed, a device to be operated, and flexible means operatively connecting said power transmission wheel to said device to be operated in such a manner that the latter is raised and lowered in synchronism with the reciprocation of said power transmission rod.

16. In a windmill operable mechanism, a power transmission wheel mountable in a windmill tower to turn in a vertical plane, a power transmission rod having one end portion operatively con-

nectable with a windwheel to impart reciprocatory movement to said rod, means carried by said power transmission wheel to connect pivotally thereto the opposite end portion of said rod at different adjustable distances from the axis about which said power transmission wheel turns, thereby to compensate for different velocities of wind to which the windwheel is exposed, a device to be operated including a weighted member, means to operatively connect said power transmission wheel to said weighted member in such a manner that the latter is raised and lowered in synchronism with the reciprocation of said power transmitting rod, said means for connecting said power transmission wheel with said weighted member comprising a cable one end portion of which is connected to said member and the opposite end portion of which is counterweighted and alternately windable upon and unwindable from said power transmission wheel, and a series of antifriction supports arranged in an inclined series whereon the portion of said cable intermediate its ends is supportable when said member is horizontally and downwardly remote from said power transmission wheel.
